JOHN F. O'CONNOR, OF CHICAGO, ILLINOIS, ASSIGNOR TO WILLIAM H. MINER, OF CHAZY, NEW YORK.

KEYLESS YOKE.

1,192,221.

Specification of Letters Patent. Patented July 25, 1916.

Application filed October 14, 1914. Serial No. 866,592.

To all whom it may concern:

Be it known that I, JOHN F. O'CONNOR, a citizen of the United States, residing at Chicago, in the county of Cook and State of Illinois, have invented a certain new and useful Improvement in Keyless Yokes, of which the following is a full, clear, concise, and exact description, reference being had to the accompanying drawings, forming a part of this specification.

10 This invention relates to improvements in keyless yokes.

An object of the invention is to provide a yoke for draft riggings which may be attached to a draw bar without the aid of keys, rivets or bolts, and so arranged that when in operative position the parts composing the yoke are self locked to prevent relative longitudinal or lateral movement.

20 Another object of the invention is to provide a keyless yoke consisting of two parts, which are united and self locked when in operative position by means of separable hinge connections.

25 The invention furthermore consists in improvements in the parts and devices and novel combinations of the parts and devices, as herein shown, described or claimed.

In the drawing forming a part of this 30 specification, Figure 1 is a side elevation of a yoke embodying my improvements, the yoke, as shown, being of the tandem variety, although as will be understood by those skilled in the art, the invention is not limited to this type of yoke. Fig. 2 is a top plan view of the structure illustrated in Fig. 1. Fig. 3 is a front end elevational view of the improved yoke, showing the same detached from the draw bar. Fig. 4 is a vertical sectional view taken substantially on the line 4—4 of Fig. 3, and Fig. 5 is a detail horizontal sectional view taken substantially on the line 5—5 of Fig. 3 of one of the parts comprising the yoke.

40 In said drawing, 10 denotes the draw bar, which is of standard form and provided with upper and lower front shoulders 11—11 and rear back wall 12. The yoke is designated generally by the reference A and, as shown, comprises two like members B B, so arranged that the yoke is split along the center thereof. Each member B comprises upper and lower arms 13—13, rear connecting piece 14 and a central post 15 which 50 forms half of a thimble in the tandem type

of yoke shown. The front ends of the arm 13 are united by a side wall or plate 16 so that when the two parts B B are assembled a box-like hood or head is provided, as clearly shown in Fig. 3, for the reception 60 of the butt of the draw bar. At their extreme forward ends, each arm 13 is provided with a shoulder 17 which is adapted to engage a portion of a shoulder 11 on the draw bar and an inwardly extending projection 65 18 having a boss 19 extending therefrom, the boss being provided with a curved surface 20 for the greater portion of its circumference and short flat faces 21 near the front thereof. Between the boss 19 and the shoulder 70 17 there is formed a groove 22, as shown most clearly in Fig. 5. To the rear of each shoulder 17 and also on the inner sides of the arms 13 are provided other shoulders 23, the shoulders 17 and 23 being spaced apart 75 a distance corresponding to the distance between the shoulders 11 and rear face 12 of the draw bar butt. As clearly shown in Fig. 5, the inner faces of the shoulders 17 and 23 are beveled, as indicated at 24—24, to facilitate the positioning of the yoke on the draw bar. At their rear ends each member B is provided with a pair of spaced ears 25—25 which are perforated and when brought into position, as clearly indicated 80 in Fig. 1, are adapted to receive therethrough a cotter 26 or other suitable retaining device.

The device is assembled as follows:—The two members B B first have their front ends brought together forward of the shoulders 11 on the draw bar, the bosses 19 of one member B being inserted in the corresponding grooves 22 of the other member B. After this is done, the two members B B 90 are brought together to the position shown in Fig. 2, whereupon the bosses 19 of each member B slide forwardly in the corresponding grooves 22 of the other member until the bosses 19 assume the position shown in dotted lines in Fig. 2. During this movement, which brings the two members B together, the shoulders 23—23 will slip by the rear wall 12 of the draw bar and thus securely clamp the draw bar between the shoulders 17 and 23. The cotter 26 is next applied. When so assembled, relative longitudinal movement of the members B B is prevented since the rearward movement of one boss 19 relative to the other member with which 100

105

110

it coöperates will tend to bring the two members B B still closer together, since it has to follow the curved surface 27. Tendency of the members B B to separate laterally is 5 also prevented, inasmuch as each boss 19 is confined between the boss of the opposite member B and the corresponding curved wall 27 thereof. Vertical separation of the parts B B is of course prevented by the 10 draw bar, since each member B has upper and lower horizontal flanges overlapping the upper and lower faces of the draw bar butt.

From the preceding description it will be seen that I have provided a keyless yoke of 15 inexpensive form and one which is particularly adapted for use on those draw bars which are not provided with slots for keys and in which it is not desirable to use rivets or bolts.

20 I claim:—

1. A yoke of the character described comprising two like members having coöperating, interengaging, integral bosses and grooves arranged to prevent either relative lateral or longitudinal movement when the parts are operatively assembled.

2. A yoke of the character described comprising two like castings each having a pocket to receive cushioning means and provided with coöperating, interengaging, integral bosses and grooves, said bosses and grooves detachably connecting said castings and preventing relative longitudinal or lateral movement when the parts are assembled.

3. A yoke of the character described com-

prising two loop members each having coöperating, interengaging bosses and grooves on the tops and bottoms thereof at the forward ends, said bosses and grooves preventing relative longitudinal or lateral movement of the parts when the same are operatively assembled.

4. A yoke of the character described, comprising two separable loop members each 45 having coöperable, integral, interfitting hinge uniting means at the front end thereof.

5. A yoke of the character described comprising, two loop members each having a 50 boss and a groove at the front end of each arm thereof, the bosses and grooves being located on the inside faces of said arms, the bosses being arranged to slide into grooves as the two loop members are swung from a 55 position where they are at an angle to each other to a position where the same are parallel.

6. A yoke of the character described comprising, two loop members each having a 60 boss and a groove at the front end of each arm thereof, the bosses of one member being arranged to slide in the grooves of the other member, each of said members having also upper and lower spaced shoulders arranged to engage the front and rear shoulders of a draw bar butt.

JOHN F. O'CONNOR.
